(57) **CLAIM**

The ornamental design for a chair, as shown and described.

DESCRIPTION

FIG. 1 is a front perspective view of a chair showing, in particular, the ornamental design thereof.

FIG. 2 is a left side view of the chair of FIG. 1. It will be understood that a right side view is a mirror image of the left side view.

FIG. 3 is a front end view of the chair of FIG. 1.

FIG. 4 is a rear end view of the chair of FIG. 1; and, FIG. 5 is a top plan view of the chair of FIG. 1.

It will be understood that the bottom of the chair is unornamented and/or not visible during normal use.

The short broken lines in the drawings represent stitching and form no part of the claimed design. The long broken lines in the drawings are included to show portions of the article and form no part of the claimed design.
